UNITED STATES PATENT OFFICE.

LOUIS L. S. BASHORE, OF MARINE CITY, MICHIGAN.

CHALK HOLDER.

1,427,712.

Specification of Letters Patent. Patented Aug. 29, 1922.

Application filed November 15, 1921. Serial No. 515,851.

To all whom it may concern:

Be it known that I, LOUIS L. S. BASHORE, a citizen of the United States, residing at Marine City, in the county of St. Clair and

5 State of Michigan, have invented a new and useful Chalk Holder, of which the following is a specification.

This invention relates to a chalk holder designed primarily for use by pool and 10 billiard players.

One of the objects of the invention is to provide means for holding ordinary cube chalk said holding means being connected by a flexible element to a spring controlled 15 reel whereby the holder with the chalk therein will be normally supported in a predetermined position but can be carried to any convenient point without attaching the flexible connection.

20 A further object is to provide a structure of this character which will automatically return the chalk to its initial position when released by the player.

A still further object is to provide a structure which is simple, durable and compact.

With the foregoing and other objects in view which will appear as the description proceeds, the invention resides in the combination and arrangement of parts and in the 30 details of construction hereinafter described and claimed, it being understood that, within the scope of what is claimed, changes in the precise embodiment of the invention shown can be made without departing from the spirit of the invention.

In the accompanying drawings the preferred forms of the invention have been shown.

In said drawings—

40 Figure 1 is a front elevation of a chalk holder.

Figure 2 is a section through the reel and its housing.

45 Figure 3 is a section through the chalk and the parts housing the same.

Figure 4 is a detail view of a modified form of hanger for the holder.

Referring to the figures by characters of reference 1 designates a reel having integral trunnions 2 extending from the centers of the sides thereof, there being annular flanges 3 providing a space therebetween in which a cord 4 can be wound. One end of this cord is adapted to be extended 50 through and suitably secured within an opening 5 formed in the reel while the other

end of the cord is adapted to be extended through an opening 6 formed within a ring 7 which constitutes part of the housing of the reel. The flanges 3 are designed to 60 work close to or in contact with this ring and screwed into each end of the ring is a disk 8 having an outwardly extending annular flange 9 which is exteriorly screw threaded. The trunnions 2 extend through 65 these disks and are seated at their outer ends within the centers of screw caps 10 which are screwed onto the projecting portions of the flanges 9 and are adapted to abut against the edges of the ring 7 thus 70 to form a complete housing for the reel. Coiled springs 11 are mounted between the disks 8 and the respective caps 10 and one end of each spring is fastened to the adjacent trunnion 2 by means of a screw 12 or 75 in any other suitable manner while the other end of the spring is suitably secured, as by means of a screw 13, to the flange 9 surrounding the spring. Thus it will be seen that when the cord 4 is unwound from the 80 reel by pulling the cord through the opening 6, the reel will be rotated against the action of the springs. When the cord is released the springs will rewind it on the reel and this winding action will be limited 85 by a stop 14 which can be in the form of a rubber ball secured to the cord near its free end.

The free end of the cord 4 is secured within the closed end of a holding cup 15 shown in Figure 3. This cup is interiorly screw threaded and is designed to receive an exteriorly screw threaded socket member 16 in which a cake of chalk indicated at 17 is seated. This socket member has an opening 95 18 therein through which the chalk is exposed and large enough to receive the end of a cue.

For the purpose of attaching the structure to a table a bracket 19 is provided and 100 to this bracket is secured a yoke 20 which straddles the housing of the reel and is secured to the respective caps 10 by means of screws 21 or in any other preferred manner. If the device is to be suspended from the 105 ceiling it is preferred to use a bracket such as shown at 22 in Figure 4, the yoke 23, which corresponds with the yoke 20, being spaced from the bracket 22 by a washer 24 and being swiveled on the bracket, the connection between the parts being effected 110 through a coupling pin or bolt 25.

It is to be understood that when the chalk is to be used the cup 15 can be grasped in the hand and the cord 4 unwound to permit the cup to be brought to any convenient position. The tip of the cue is inserted into the opening 18 so as to engage the chalk and when the cup 15 is released the tensioned springs 11 will promptly rewind the cord until the cushioning stop 14 comes against the ring 7 as shown in Figure 1.

It will be understood that the chalk can be renewed readily and by providing a structure such as described the chalk can be located easily and will not be wasted or lost.

What is claimed is:—

1. A device of the class described including a reel, a ring surrounding the reel, flanged disks seated in the ends of the ring, screw caps engaging the flanges on the disks, trunnions extending from the reel and journaled within the disks and caps, springs housed between the disks and caps and secured to the trunnions and flanged disks at their respective ends, a chalk holding device, and a flexible connection between said device and the reel, there being an opening within the ring in which said flexible connection is slidably mounted.

2. In a device of the class described a ring, flanged disks closing the ends of the ring, screw caps engaging the flanges on the disks, a reel interposed between the disks, trunnions extending therefrom and journaled within the disks and caps, coiled springs housed between the disks and their caps, each spring being secured at one end to a trunnion and at its other end to a flanged disk, a chalk holding device, and a

flexible connection between said device and the reel and movable through an opening in the ring, said connection being normally wound upon the reel by the springs.

3. A device of the class described including a ring, a reel therein, flanged disks removably mounted in the ends of the ring and cooperating therewith to house the reel, screw caps engaging the flanges on the disks, trunnions extending from the reel, coiled springs secured to the trunnions and to the flanges on the disks for controlling the rotation of the reel, a chalk holding device, a flexible connection between said device and the reel extending through an opening in the ring, and a resilient stop device upon said connection and movable against the ring.

4. A device of the class described including a ring, a reel therein, flanged disks removably mounted in the ends of the ring and cooperating therewith to house the reel, screw caps engaging the flanges on the disks, trunnions extending from the reel, coiled springs secured to the trunnions and to the flanges on the disks for controlling the rotation of the reel, a chalk holding device, a flexible connection between said device and the reel extending through an opening in the ring, a yoke secured to the caps, and an attaching bracket secured to the yoke.

In testimony that I claim the foregoing as my own, I have hereto affixed my signature in the presence of two witnesses.

LOUIS L. S. BASHORE.
